UNITED STATES PATENT OFFICE.

ROBERT GORTON, OF NEWTON, MASSACHUSETTS.

GARMENT-SUPPORTER.

SPECIFICATION forming part of Letters Patent No. 654,727, dated July 31, 1900.

Application filed April 14, 1900. Serial No. 12,793. (No model.)

To all whom it may concern:

Be it known that I, ROBERT GORTON, a citizen of the United States, residing at Newton, in the county of Middlesex and State of Massachusetts, have invented certain new and useful Improvements in Garment-Supporters, of which the following is a specification.

My invention relates particularly to that class of garment-supporters known as "hose" supporters, in which the clasp-carrying straps are suspended from a buckle, which is in turn provided with a strap carrying a device at its upper end for attachment to a part of the garments above the hose. My improvement may, however, be applied to hose-supporters of other forms and to other kinds of garment-supporters.

A well-known and extensively-used hose-supporter is that in which a buckle, consisting of a slotted base-plate and a hinged clamping-lever, supports a pair of elastic straps or pendants which depend from it and carry at their lower ends clasps that engage the upper ends of the hose, while an elastic buckle-suspending strap is adjustably secured between the clamping-lever and the base-plate of the buckle. One of the elastic clasp-carrying straps has its upper end passed through the slot in the lower end of the base-plate and then turned down and extended below the lower edge of the plate, while the other elastic clasp-carrying strap is carried up along the back of the plate, bent over the upper edge thereof, extended down along the front of the plate behind the clamping-lever, then threaded through the slot, and extended below the lower edge of the plate, the four thicknesses of the elastic webbing of the clasp-carrying straps being stitched together by one or more lines of stitching just below the lower edge of the buckle. By this arrangement the metal back of the buckle is covered, thus preventing it from coming in contact with the person or garments of the wearer, and the front of the base-plate above the slot is also covered. While this form of hose-supporter has been extensively used for some time, it nevertheless has serious defects, among which are, first, the elastic webbing being of loose texture and stretchable; it is difficult to make the lines of stitching true, as the material is apt to twist and draw; second, owing to the loose nature

of the material the stitching is apt to break loose when subjected to more than moderate strain; third, the use of elastic material for covering the buckle is expensive, as an extra amount of this costly material is employed; fourth, in the use of such an arrangement the elastic covering on the front of the plate beneath the lever tightens or stretches when the clamping-lever is closed down, so that when the strain on the hose-supporter is relieved, as when the wearer sits down or the clasps are released, the webbing at the front of the plate relaxes, and this tends to throw the clamping-lever open; fifth, when the lever is closed down it stretches the webbing at the front of the buckle, as before stated, and this causes the webbing along the back of the plate to slacken or bulge, making a clumsy appearance, which in use is apt to increase rather than decrease, and, sixth, when in "taking up" or adjusting the buckle-supporting strap it is drawn through the buckle unevenly—i.e., diagonally, as is sometimes carelessly done—a cornerwise pull is given to the buckle, causing the clasp-carrying straps to slide along the slot in the plate to one side thereof, thus throwing the entire hose-supporter out of shape. My present invention is primarily designed to remedy these defects in a hose-supporter of the general class just described.

Instead of covering the base-plate of the buckle with a portion of the elastic webbing I use for this purpose a piece of inelastic material and preferably secure the upper ends of the elastic straps which carry the clasps to the ends of the inelastic covering which project below the buckle.

My improvements may be applied in a number of ways, some of which are illustrated in the accompanying drawings, in which—

Figure 1 shows a front elevation of a hose-supporter of the kind to which my improvements are primarily intended to be applied. Fig. 2 shows a vertical central section through the buckle, the buckle-covering, the clasp-carrying and buckle-suspending straps. Figs. 3, 4, 5, and 6 are views similar to Fig. 2, showing modifications. Fig. 7 is a view similar to Fig. 2, showing an arrangement in which a non-elastic strap is employed to carry the clasps and to also cover the base-plate of the buckle. Fig. 8 is a view similar to Fig. 2,

showing an arrangement in which a non-elastic strap is employed to suspend the buckle, to cover it, and to also form a loop to which another strap or straps may be attached.

5 Figs. 9 to 12 show further modifications. Fig. 1 serves to illustrate in general outline both the old form of hose-supporter, to which my invention is especially intended to be applied, and a hose-supporter constructed according to one form of my invention.

B indicates the buckle, A the buckle-suspending strap, and C the clasp-carrying straps or pendants. The strap A is provided at its upper end with a device, such as a safety-pin, by means of which it may be secured to some part of the garments above the hose, while the straps C are provided at their lower ends with clasps D, comprising loops and buttons of well-known construction; but of course the lower ends of the straps C may be formed with buttonholes or provided with other forms or devices for attachment to the hose or other garment. The buckle is shown in each figure of the drawings as consisting of 25 a base-plate E and a clamping-lever F. The base-plate is provided with a slot e, and the lever is hinged to lugs e', projecting from the front of the base-plate near its upper end. The lever is L-shaped in longitudinal section, 30 the longitudinal portion f extending down along the front of the base-plate when the lever is closed, while the short portion f' is adapted to engage with and clamp the webbing when the lever is closed.

35 The buckle-suspending strap A in Figs. 1, 2, 3, 4, and 5 is preferably of elastic webbing, and it extends down between the lever and the front of the base-plate and is adjusted in the usual way. The clasp-carrying straps 40 C are suspended from the base-plate in different ways, while that portion of the base-plate above the slot e is covered by a separate piece of material G. In Fig. 2 the covering G, which is of some inelastic material, such as satin, 45 extends along the back of the base-plate over the top thereof and down along the front. One end of the covering is passed through the slot e and is extended down below the lower edge of the buckle and lies behind the other 50 end of the covering, which also extends below the lower edge of the buckle. The covering G is of sufficient width to entirely or approximately cover the entire back face of the buckle and also the front face thereof above the slot 55 e. One of the clasp-carrying straps C in Fig. 2 has its upper end terminated in line with the lower wall of the slot e, while the other strap C has its end passed through the slot and extended down below the lower edge of 60 the buckle. One end of the covering G is extended around this end of the strap C and then prolonged up between the overhanging end of this strap and the end of the other clasp-carrying strap. Lines of stitching H 65 are employed to connect the several thicknesses together below the base-plate, and in this instance the stitching passes through six

thicknesses of material. The important feature, however, is that inelastic material is employed for covering the greater portion of the 70 base-plate, while the elastic webbing is secured to said inelastic material.

The precise manner of disposing the ends of the webbing and the covering may be considerably varied. Thus in Fig. 3 only one 75 clasp-supporting strap is employed, the end of which passes through the slot e, extends down below the lower edge of the buckle, and is stitched to the three thicknesses of the covering below the plate and to the webbing on 80 the other side of the buckle, of which it forms a part. In other respects the construction shown in Fig. 3 is similar to that shown in Fig. 2, except that the base-plate is of a little different shape.

In Fig. 4 the clasp-supporting straps are formed of one piece of webbing which merely passes through the slot e, its two ends carrying the clasps. The covering G is arranged substantially as shown in Fig. 2, except that 90 one end of the covering which extends below the base-plate is longer than the other and is turned up behind the other end, the three thicknesses of the covering thus formed being stitched to the two thicknesses of the 95 webbing C.

In Fig. 5 the base-plate is of the form shown in Fig. 3. The covering extends over the upper edge of the base-plate and covers both the front and rear of the base-plate above the 100 slot, but in this instance the two ends of the covering extend down from the back of the base-plate instead of from the front, as in Figs. 2, 3, and 4. The upper ends of both clasp-supporting straps C extend up to the 105 front of the slot e, pass through it, and then extend down below the lower edge of the plate. One end of the covering G extends up between the overhanging ends of the straps C and the adjacent portions thereof. The stitching extends through four thicknesses of the webbing C and three thicknesses of the covering G.

In Fig. 6 the frame of the buckle is the same as in Fig. 2; but one of the clasp-supporting straps C has its upper end arranged below the 115 lower edge of the buckle, while the upper end of the other clasp-supporting strap extends through the slot e and down below the lower edge of the buckle, as in Fig. 2. In this instance the buckle-suspending strap A instead 120 of having a free lower end has its lower end looped and made to lie beneath the overhanging end of the clasp-supporting strap. One of the depending ends of the covering G is carried up between the overhanging end of the 125 strap C and the upturned end of the strap A. The stitching H secures the several ends together, passing through four thicknesses of elastic webbing and three thicknesses of inelastic material.

None of the defects or disadvantages found in the old form of hose-supporter, such as I have before mentioned, are present in hose-supporters constructed in the manner indi-

cated in Figs. 2 to 6, inclusive. The stitching does not break loose or draw, because the inelastic material G is strong and firm and holds the stitching true. When the lever F is closed down in adjusting the strap A, it does not stretch the covering G, and therefore there is no tendency to relax and open the lever and no tendency to cause a bulging or fullness on the rear side of the base-plate. 5 The inelastic material, such as satin, is much less expensive than elastic webbing. The general construction before described is the one preferred—namely, that in which the straps which are to be attached to the lower garment 10 are of elastic material and the covering of the buckle is of inelastic material. 15

Figs. 7 and 8 show how where the straps for supporting the lower garment are made of inelastic material the buckle may be covered by this same material. In both Figs. 7 and 8 the form of buckle is substantially the same as that hereinbefore mentioned, though of course I do not intend to be limited to the precise form of buckle employed in any instance. 20 In Fig. 7 the straps C are shown as made of one piece of inelastic webbing; but instead of merely hanging from the slot e the webbing first passes up along the lower part of the back of the base-plate, then through 25 the slot e, then over the top of the base-plate, then down along the back of the base-plate and below the buckle. The buckle-suspending strap A passes between the base-plate and the lever, but has its lower end looped and 30 secured by lines of stitching H to the two thicknesses of the straps C below the buckle. In Fig. 8 a single piece of inelastic material is used to constitute the buckle-suspending strap and a loop to which a garment-supporting device may be applied. The strap has 35 one end extending over the top of the base-plate. This end passes down the front of the base-plate and then through the slot e. The other end of the strap passes down in rear of 40 the base-plate and is secured to the overhanging end by stitches H below the slot. The strap then forms a loop h and then passes up in rear of the clamping-lever and between it and the covered base-plate. In both instances 45 (shown in Figs. 7 and 8) the base-plate is covered with inelastic material and the covering serves to support the depending garment-supporting straps. 50

In Fig. 9 the clasp-supporting straps are sustained entirely by the covering G—i. e., the straps do not extend through the slot e. The strap A is adjustably secured between the clamping-lever and the covered base-plate and in this instance may be secured to 55 the covering G and the straps C, as illustrated.

In Fig. 10 the lower end of the strap A is passed through the slot e, and the upper ends of the straps C are stitched to the upturned 60 and overhanging parts of the strap A and to the depending ends of the covering. In Fig. 11 the covering G covers that part of the base-

plate above the slot e, but does not extend below the slot. The straps C extend through the slot, and the upturned end of the strap A 70 is secured between the upper portion of the straps C and the overhanging ends thereof below the buckle.

In Fig. 12 the covering G covers only that portion of the base-plate above the slot. The 75 lower end of the strap A is free and the strap C extends through the slot, the two folds being stitched together below the base-plate. The ends of the covering are secured together above the base-plate. The covering may be 80 left in this condition or it may be slipped around so as to bring the stitched ends into the slot, as shown in Fig. 11.

I claim as my invention—

1. The combination with a buckle, comprising 85 a base-plate and a clamping device, of a covering of inelastic material arranged along the front and rear faces of the base-plate, and an adjustable buckle-suspending strap interposed between the clamping device and the 90 covered front face of the base-plate.

2. The combination with a buckle, comprising 95 a base-plate and a hinged clamping-lever, of a covering of inelastic material arranged along the front and rear faces of the base-plate, and an adjustable buckle-suspending strap interposed between the hinged clamping-lever and the covered front face of the 100 base-plate.

3. The combination with a buckle, comprising 105 a base-plate and a clamping device, of a covering of inelastic material arranged along the front and rear faces of the base-plate, an adjustable buckle-suspending strap interposed between the clamping device and the 110 covered front face of the base-plate and a strap suspended from the buckle and provided with a device for attachment to a garment.

4. The combination of a buckle, comprising 115 a base-plate and a clamping device, a covering of inelastic material arranged along the front and rear faces of the base-plate, a buckle-suspending strap, interposed between the clamping device and the covered base-plate and a pendent strap of elastic webbing 120 supporting an attaching device and secured to the inelastic material.

5. The combination with a buckle, comprising 125 a base-plate and a clamping device, of a covering of inelastic material secured to the base-plate, a suspending-strap interposed between the base-plate and the clamping device, an attaching device adapted to be secured to the suspended garment and a strap to which 130 the attaching device is secured and which is secured to the buckle-covering.

6. The combination with a buckle, comprising 135 a base-plate and a clamping device, of a piece of inelastic material secured to the base-plate and depending below the lower edge thereof, an attaching device adapted to be secured to the suspended garment, a strap of elastic material to which the attaching device

is secured and which is suspended from the base-plate and is attached to the depending end of the piece of inelastic material.

7. The combination of a buckle, comprising a slotted base-plate and a hinged clamping-lever, a covering for the base-plate of inelastic material, an elastic strap, the upper end of which passes through the slot and is secured to the buckle-covering, and a buckle-suspending strap adjustably secured to the buckle between the clamping-lever and the covered base-plate.

8. The combination of a buckle, comprising a slotted base-plate, and a hinged clamping-lever, a covering of inelastic material extending across the front of the base-plate over the upper edge thereof down along the back of the base-plate and through the slot, and an elastic strap of elastic webbing extending through the slot and secured to the buckle-covering.

9. The combination of a buckle comprising a base-plate and a clamping device, a buckle-suspending strap interposed between

the clamping device and the base-plate, a garment-supporting strap suspended from the buckle, a covering of inelastic material arranged over the front and rear faces of the base-plate and having its lower ends secured to and between folded portions of the upper ends of the elastic straps.

10. The combination of a buckle, comprising a slotted base-plate, a hinged clamping-lever, a covering for the buckle of inelastic material which extends through the slot and over the top of the base-plate, and downward below the lower edge of the base-plate, and an elastic strap also extending through the slot of the base-plate and having a downwardly-projecting end which extends between folds of the buckle-covering and is stitched thereto.

In testimony whereof I have hereunto subscribed my name.

ROBERT GORTON.
